TIMING OF FUEL INJECTION SYSTEMS

Donald E. Meitzler, Manchester, Conn., assignor
to United Aircraft Corporation, East Hartford,
Conn., a corporation of Delaware

Application July 23, 1943, Serial No. 495,929

6 Claims. (Cl. 103—154)

1

This invention relates to fuel injection apparatus particularly for free-piston engine-and-compressor units.

The co-pending Meitzler application, Serial No. 486,625, filed May 11, 1943, shows a free-piston unit in which the injection pump is mounted within the pinion which forms a part of the restraining linkage for the opposed pistons. Oscillation of the pinion reciprocates the plunger. A feature of this invention is an adjustment by which to change the position of the stroke of the plunger with respect to the oscillating stroke of the pinion.

In this type of apparatus the injection of fuel is controlled by the position of the injection plunger within the cylinder, and the changes in the position of the plunger stroke may be used for varying the period of fuel injection into the engine cylinder. Another feature of this invention is an adjustment of the plunger stroke for changing the injection cycle. Another feature is the adjustment of the plunger stroke with respect to the stroke of the pinion by angular movement of a part of the connecting structure between the pinion and plunger.

Other objects and advantages will be apparent from the specification and claims, and from the accompanying drawing which illustrates what is now considered to be a preferred embodiment of the invention.

Fig. 1 is a side elevation of the free-piston engine-and-compressor unit.

Fig. 2 is a sectional view through the restraining pinion and the injection pump.

The unit shown includes an engine cylinder 10 having reciprocating pistons 12 and 14 to which compressor pistons 16 and 18 in cylinders 20 and 22 are integrally connected. Sleeves 24 and 26 attached to the compressor pistons complete the reciprocating piston assemblies. The sleeves in combination with stationary pistons 28 and 30 form air spring cylinders.

The piston assemblies are moved apart by the burning of fuel injected into engine cylinder 10 by one or more devices 32. Air compressed in the air spring cylinders on the power stroke returns the piston assemblies. The assemblies are maintained at equal distances from the center of the engine cylinder by a linkage which may include racks 34 on the compressor pistons engaging opposite sides of a pinion 36.

Intake manifold 38 conducts air to intake valves 40 through which air alternately enters opposite ends of the compressor cylinders. The compressed air leaves the cylinders through discharge

2

valves 42, also at opposite ends of the compressor cylinders, and passes through scavenge manifold 44 through ports 46 and 48 which are uncovered by pistons 12 and 14 at the end of the power stroke, thereby permitting air to be blown through the engine cylinder and exhaust ports 50 and 52 into exhaust manifold 54.

As shown in Fig. 2, pinion 36 is supported in a housing 56 forming part of the injection device 10 which is mounted in a tubular bracket 58. Housing 56 provides a bearing for a shaft 60 integral with the pinion. This shaft is also supported by a ring 62 in housing 56. A radial flange 64 on the shaft is held between the end of bearing 62 and a thrust ring 66 to prevent endwise movement of the pinion.

The inner surface of sleeve 60 is provided with a helix 68 which engages several spaced shoes 70 on a cup 72 positioned over a casing 74 in which an injection plunger 76 is movable. A coil spring 78 moves the cap axially to hold the shoes in contact with the helix. As the pinion oscillates, the plunger 76 is moved longitudinally in its bore 80 in the casing 74 for injection of fuel into the engine. A coil spring 82 moves the plunger 76 on its return stroke.

The injection system shown is of the accumulator type, and casing 74 has opposed accumulator chambers 84 and 86 interconnected by a passage 88. Fuel from the end of bore 80 reaches chambers 84 and 86 through a groove 90 in an accumulator valve 92 which slides in a bore in a ring 96 in the casing 74. Fuel escapes from accumulator chambers through a passage 98 and past a check valve 100 to the nozzle 104. The accumulator valve 92 moves lengthwise to engage a seat 106 at the end of passage 98 or a seat 108 closing the groove 90. Check valve 100 is held against its seat by a spring 109 which determines the pressure at which injection of fuel from chambers 84 and 86 is cut off.

As the plunger is moved on the injection stroke, fuel which was directed to the end of bore 80 through an inlet port 110 is forced into the accumulator chambers through groove 90 until a discharge port 112 is uncovered by a groove 114 in the plunger. This groove 114 connects with the head of the plunger through a passage 116 (shown in dotted lines). When port 112 is uncovered, the pressure at the end of the plunger drops suddenly so that valve 92 moves against seat 108 and permits fuel to discharge through the nozzle.

The position of the plunger stroke within the bore of the oscillating pinion may be adjusted by

turning the cup 72 angularly, thereby changing the position of shoes 70 with respect to the helix. This adjustment may be effected by a gear 120 carried by a cap 122 on housing 58. This gear is splined to cup 72 and meshes with a worm 124 mounted in the cap. Worm 124 has a shaft projecting out of the housing (not shown) by which the worm may be turned manually or mechanically. When the angular position of cup 72 is changed by turning the worm to vary the position of the plunger stroke, the point at which fuel injection occurs with respect to the engine piston stroke will also be varied.

It is to be understood that the invention is not limited to the specific embodiment herein illustrated and described, but may be used in other ways without departure from its spirit as defined by the following claims.

I claim:

1. Fuel injection apparatus for a free-piston engine-and-compressor unit having opposed pistons and a restraining linkage connecting said pistons including an oscillating pinion, said apparatus including an injection plunger, a cylinder in which said plunger reciprocates, said plunger and cylinder having cooperating injection control means dependent upon the longitudinal position of the plunger in the cylinder, means including a helix and follower connecting said pinion and plunger for reciprocating the plunger in response to oscillation of the pinion, and means for adjusting the longitudinal position of the plunger with respect to said connecting means to shift the plunger stroke longitudinally within the cylinder.

2. Fuel injection apparatus for a free-piston engine-and-compressor unit having opposed pistons and a restraining linkage connecting said pistons including an oscillating pinion, said apparatus including a cylinder, a plunger longitudinally movable in said cylinder, a port in said cylinder and a cooperating groove in said plunger for procuring a change in the injection operation when said groove and port are in communication, a helix and a cooperating follower connecting the pinion and plunger for reciprocating the plunger in response to oscillation of said member, and means for adjusting the longitudinal position of the plunger with respect to said pinion, thereby shifting longitudinally the stroke of the plunger.

3. Fuel injection apparatus for a free-piston engine-and-compressor unit having opposed pistons and a restraining linkage connecting said pistons including an oscillating pinion, said apparatus including a cylinder, a plunger longitudinally movable in said cylinder, a port in said cylinder and a cooperating groove in said plunger for procuring a change in the injection operation when said groove and port are in communication, a helix on said pinion and a cooperating follower connected to the plunger, and means for turning the follower angularly to change the relative positions of the helix and plunger thereby shifting longitudinally the stroke of the plunger.

4. Fuel injection apparatus for a free-piston engine-and-compressor unit having opposed pistons and a restraining linkage connecting said pistons including an oscillating pinion, said apparatus including a cylinder, a plunger longitudinally movable in said cylinder, a port in said cylinder and a cooperating groove in said plunger for procuring a change in the injection operation

when said groove and port are in communication, a helix on said pinion and a cooperating follower connected to the plunger, and means including a gear and a cooperating pinion for turning the follower angularly to change the relative positions of the helix and plunger.

5. Fuel injection apparatus for a free-piston engine-and-compressor unit having opposed pistons and a restraining linkage connecting said pistons including an oscillating pinion, said apparatus including a casing having a bore, a pump plunger longitudinally movable in said bore for pumping fuel into the unit, a port communicating with said bore, and a cooperating groove in said plunger for procuring a change in the injection operation when said groove and port are in communication, said casing being located in part within the oscillating pinion with the longitudinal axis of the plunger parallel to the axis of oscillation of the pinion, a helix and a cooperating follower connecting the pinion and plunger for reciprocating the plunger in response to oscillation of said pinion, and means independent of the pinion oscillation for adjusting the longitudinal position of the plunger with respect to said pinion, thereby shifting longitudinally the stroke of the plunger.

6. Fuel injection apparatus for a free-piston engine-and-compressor unit having opposed pistons and a restraining linkage connecting said pistons including an oscillating pinion, said apparatus including a casing having a bore, a pump plunger longitudinally movable in said bore for pumping fuel into the unit, a port communicating with said bore, and a cooperating groove in said plunger for procuring a change in the injection operation when said groove and port are in communication, said casing being located in part within the oscillating pinion with the longitudinal axis of the plunger parallel to the axis of oscillation of the pinion, a helix on said pinion, and a cooperating follower engaging said helix, said follower being connected to the plunger and being movable axially through the pinion as the latter oscillates, and means for turning the follower angularly to change the relative positions of the helix and follower, thereby shifting longitudinally the stroke of the plunger within the bore.

DONALD E. MEITZLER.
